UNITED STATES PATENT OFFICE.

ELMER C. BASSETT, OF MILTON, MASSACHUSETTS, ASSIGNOR TO THE REECE BUTTON HOLE MACHINE COMPANY, OF BOSTON, MASSACHUSETTS, A CORPORATION OF MAINE.

STOP-MOTION.

1,173,162.

Specification of Letters Patent. Patented Feb. 29, 1916.

Application filed July 8, 1915. Serial No. 38,773.

To all whom it may concern:

Be it known that I, ELMER C. BASSETT, a citizen of the United States, residing at Milton, county of Norfolk, State of Massachusetts, have invented an improvement in Stop-Motions, of which the following description, in connection with the accompanying drawing, is a specification, like characters on the drawing representing like parts.

This invention relates to stop motions for sewing machines and the like, and the objects of the invention are to provide a simple stop motion which is constructed to bring the machine to rest with an easy cushioning movement and without any jar or shock, and also to provide a novel stop motion in which when the machine is to be stopped the belt is shifted from the fast to the loose pulley in advance of the action of the stop device, thereby giving sufficient time for the belt to be fully shifted from the fast to the loose pulley before the machine is to be brought to rest. This is especially advantageous in high speed machines because it insures that the machine will not be brought to rest until after the driving belt has been fully shifted onto the loose pulley.

In order to give an understanding of my invention I have illustrated in the drawings a selected embodiment which will now be described, after which the novel features will be pointed out in the appended claims.

Figure 1 of the drawings is a side view of a portion of a machine having one form of my improved stop motion applied thereto; Fig. 2 is an underside view of the machine showing one means for automatically throwing the stop motion into operation; Fig. 3 is a top plan view of the stop mechanism; Fig. 4 is a vertical sectional view thereof; Figs. 5, 6, 7, 8, 9, and 10 are side and plan views respectively of the stop cam in different positions; Fig. 11 is a section on the line $\alpha-\alpha$, Fig. 1. Fig. 12 is a detail of the cam for releasing the locking member.

I wish to state at the outset that my invention is applicable not only to sewing machines, but to other similar machines and is especially applicable for use in connection with high speed machines.

1 designates the frame of the machine which is provided with a driving shaft 2 by

which it is operated. This shaft is shown as having a pulley 3 fast thereon and a pulley 4 loose thereon.

5 is a driving belt which is adapted to be shifted from the loose to the fast pulley for driving the machine and back to the loose pulley again when the machine is to be stopped. The belt is operated by a belt shifter 6 which is herein shown as carried by a rock shaft 7 mounted in bearings 8 carried by the frame 1. This rock-shaft can be turned to throw the belt from the fast to the loose pulley or vice versa by any suitable means. I have herein shown for this purpose a handle 9 fast on the rock-shaft and have also shown said rock-shaft as provided with an arm 10 to which a treadle 76 may be suitably connected, thus making it possible to shift the belt either by hand or by a treadle. In some machines the belt shifter is held in position to retain the belt on the fast pulley by continued pressure on the treadle, and in some other machines a locking device or catch is employed which holds the belt on the fast pulley until said locking device is released when the machine is to be stopped. In the embodiment of the invention herein illustrated I have shown a construction of the latter type, and 11 designates a locking pawl pivoted on a stud 12 carried by the frame of the machine and acted upon by a suitable spring 13, said spring operating to throw the dog into locking engagement with the arm 10 when the latter is depressed, thereby locking the belt shifter in the position to maintain the belt on the fast pulley. When the locking pawl 11 is released the belt shifter will be thrown into position to carry the belt onto the loose pulley by means of a spring 14 which is herein shown as acting on an arm or plate 15 fixed to the rock-shaft 7, said spring being confined between said plate and the frame of the machine.

The means for bringing the machine to rest when the belt is shifted to the loose pulley is of that type including a stop cam 100 fast on the driving shaft 2 and having an eccentric surface and a spring-pressed stop dog adapted to be thrown into engagement with the eccentric surface when the belt is shifted to the loose pulley whereby the dog 105 will apply an increasing frictional break-

ing pressure to the cam as the shaft rotates.

The stop cam is shown at 16 and it may be rigidly secured to the driving shaft 2 in any suitable way. Said cam is formed to present the eccentric portion 17 which merges into the straight-faced portion 18. Said cam is also formed with the inclined face 19, the inner edge 20 of which is concentric with the shaft.

The stop dog which coöperates with the stop cam in stopping the machine is shown at 21. Said stop dog is provided with the flat face 22 that engages the stop cam and is carried by a shank 23 that is slidably mounted in bearings 24 formed in a frame or carrier 25 which is herein shown as sustained on the rock-shaft 7. This stop dog is acted upon by a spring 26 which is herein shown as encircling the shank 23 and as bearing at one end against one of the bearings 24, and at the other end against a collar 29 adjustably mounted on the shaft 23.

30 is a stop collar fast on the shaft 23 and adapted to engage one of the bearings 24 for limiting the expansive movement of the spring 26. This collar is provided with the forked portion 31 which straddles the frame 25 and prevents turning movement of the shank.

A connection between the frame or carrier and the rock-shaft is provided by which when the rock-shaft is turned to shift the belt onto the fast pulley 3, the frame is moved into position to carry the stop dog to one side of the stop cam 16, while when the belt shifter is shifted to carry the belt onto the loose pulley, the frame 25 will be moved to carry the stop dog into position to engage the stop cam 16. When the belt shifter is moved to carry the belt onto the loose pulley the stop dog will move over the inclined face 19 of the stop cam so as to bring the square end 22 thereof against the face of the stop cam. As the shaft rotates the eccentric portion 17 of the stop cam acts on the stop dog 21 and forces it rearwardly against the spring 26 whereby an increasing frictional braking pressure is applied to the stop cam. As the shaft continues to rotate the braking pressure increases with the increasing eccentricity of the portion 17 until the cam is turned sufficiently to bring the flat face 18 against the flat face 22 of the dog, as shown in Fig. 1. If the machine has not been completely brought to rest at this time, the further continued movement of the cam will cause the flat face 18 thereof to act on the point 27 of the dog, as shown in dotted lines Fig. 9, thus bringing the machine to rest with a cushioning or yielding action.

It will be noted that the point 27 of the stop dog against which the flat face 18 operates when the stop cam is in the dotted line position shown in Fig. 9 is situated out

of the axial line of the shank and considerably above the axial line of the shaft. 2. As a result a slight angular turning movement of the stop cam will place the spring 26 under a very greatly increased tension 70 and, therefore, the shaft 2 will be quickly brought to rest after it has passed the position shown in Fig. 1. This final movement of the shaft in coming to rest will, however, be a cushioned movement which will be free 75 from shock or jar. It will be understood, of course, that after the forward rotation of the shaft is stopped, the action of the spring 26 will turn the shaft 2 backwardly slightly until the flat face 22 of the stop dog 80 rests flatly against the flat face 18 of the stop cam, as shown in Fig. 1. The eccentric portion 17 of the stop cam coöperates with the stop dog 21 to provide a brake device for gradually bringing the shaft to rest, and 85 the flat face 18 of the stop cam coöperates with the flat face 22 of the stop dog and the corner 27 thereof to bring the shaft to rest quickly but with a cushioned movement.

The stop dog 21 is so sustained that the 90 axial line of the shank 23 thereof intersects the diameter of the shaft 2; and the straight face 18 of the stop cam is so shaped that the point 28 thereof where a radial line perpendicular to the face 18 would intersect the latter is a less distance from the center of the shaft than the point 29 where the eccentric portion 17 merges into the straight portion. As a result, when the stop dog 21 leaves the eccentric portion 17 and comes 95 onto the straight portion 18, the frictional pressure will be released slightly until the parts come into the position shown in Fig. 1, after which the frictional braking pressure will be increased, as above described. 105

One feature of my invention relates to a construction whereby when the machine is stopped the belt shifter will be operated to shift the belt onto the loose pulley prior to the movement of the frame 25 that brings 110 the stop dog 21 into engagement with the stop cam, thus giving time for the belt to be completely shifted onto the loose pulley before the machine is brought to rest. This feature has especial advantage in a high speed machine. I accomplish this herein by making the frame or carrier 25 capable of movement relative to the rock-shaft and providing a construction which prevents the frame 25 from moving until after the belt shifter has been given its movement. 115

The carrier 25 is shown as loosely mounted on the rock-shaft 7, and the arm or plate 15 is provided with an extension 32 that overlies the frame so that when the rock-shaft is turned to shift the belt from the loose to the fast pulley, the engagement of the extension 32 with the frame will move it into a position to carry the stop dog 21 out of engagement with the stop cam 16. The 120 125 130

frame 25 is acted upon by a suitable spring 33 which tends to move it laterally into a position to carry the stop dog 21 into the plane of movement of the cam 16. When 5 the rock-shaft 7 is turned to shift the belt to the loose pulley the frame 25 will be prevented from swinging outwardly under the action of the spring 33 by the engagement of the stop dog with some portion of the 10 stop cam outside of the eccentric face, which portion is referred to generally by the numeral 34. This is the position shown in Figs. 5 and 6. As the stop cam turns and the inclined face 19 comes opposite the stop 15 dog, as shown in Figs. 7 and 8, then said stop dog will move down the inclined face under the action of the spring 33, thus bringing said dog into position to engage the eccentric portion 17 of the stop cam 16. 20 There is, however, a sufficient interval of time between the shifting of the belt shifter and the movement of the frame 25 to permit the belt to be completely shifted onto the loose pulley before the stop dog comes into 25 engagement with the eccentric face 17 of the stop cam and begins to apply a frictional braking pressure thereon.

Where a locking pawl such as 11 is used for holding the belt shifter on the fast pulley, the operation of stopping the machine involves releasing this locking pawl. In the illustrated embodiment of my invention I have shown means for automatically releasing this pawl at the end of a predetermined 30 cycle of movements. Such means comprises a cam 35 on a rotary part 36 of the machine, which cam is adapted to engage an arm 37 extending from the locking pawl 11 when the part 36 reaches a predetermined point in its rotation, thus releasing the latch. The parts are so timed that this release of the latch 11 will take place when the stop cam is in such a position that the portion 34 thereof is opposite the stop dog 21 with the result that when the latch is released the stop 40 dog will come against the portion 34 of the cam and thus be prevented from moving over into its operative position until the cam has rotated sufficiently to bring the inclined face 19 opposite the stop dog. The belt shifter will, however, be shifted to carry the belt onto the loose pulley as soon as the locking dog 11 is released and, therefore, there will be an interval of time elapsing between 45 the shifting of the belt onto the loose pulley and the action of the stop dog on the eccentric portion of the stop cam which is sufficient to insure that the belt will be entirely shifted onto the loose pulley before the stop dog begins to apply its braking pressure.

My invention is applicable to machines of various types and while I have illustrated herein a selected embodiment of my invention I do not wish to be limited to the constructional features shown.

I claim

1. In a stop motion, the combination with a driving shaft having fast and loose pulleys thereon, of a belt shifter for shifting the belt from one pulley to the other, means 70 for actuating said shifter, a stop cam fast on the shaft and provided with an eccentric surface, and a spring-pressed stop member adapted to engage said surface and thereby bring the shaft to rest, a support for said 75 stop member, said stop cam having associated therewith means controlling the movement of said support whereby the stop member is prevented from coming into operative engagement with the stop cam until after the belt shifter has been shifted into position to bring the belt onto the loose pulley.

2. In a stop motion, the combination with a driving shaft, of a driving element therefor, means to establish an operative or non-operative connection between said driving element and driving shaft, a stop cam fast on the driving shaft, said stop cam being provided with an eccentric surface which merges into a straight surface, a stop member, means supporting said stop member for movement in a direction at right angles to the axis of said shaft, said stop member having a substantially flat face extending in a plane at right angles to its direction of 95 movement, a spring acting on the stop member, and means to move said stop member into engagement with the eccentric face of the stop cam when the driving element is disconnected from the driving shaft, the flat 100 face of the stop member cooperating with the flat face of the stop cam to bring the driving shaft to rest with a cushioned movement.

3. In a stop motion, the combination with 105 a driving shaft having a fast and a loose pulley thereon, of a rock-shaft, a belt shifter fast on the rock-shaft, a stop cam fast on the driving shaft, a frame loosely pivoted on the rock-shaft, and a spring-pressed stop 110 member carried by said frame, said stop cam having associated therewith means to hold the stop member from operative engagement therewith for a time interval after the belt shifter is operated to throw the belt onto the 115 loose pulley.

4. In a stop motion, the combination with a driving shaft, of a fast and a loose pulley thereon, a belt shifter for transferring the driving belt from one pulley to the other, 120 means to actuate the belt shifter, a stop cam fast on the shaft and having an eccentric surface, a spring-pressed stop member adapted to engage said surface to bring the shaft to rest, and means supporting said 125 stop member for movement into and out of operative position independently of the belt shifter, said stop cam having provision for holding the stop member out of operative position while the driving shaft makes a 130

partial revolution after the belt shifter has been operated.

5. In a stop motion, the combination with a driving shaft having a fast and loose pulley thereon, of a rock shaft, a belt shifter rigid with the rock shaft for shifting a belt from one pulley to the other, a stop cam fast on the driving shaft, a frame mounted on the rock shaft and capable of a limited 10 turning movement relative thereto, a spring-pressed stop member carried by said frame and movable therein in a direction at right angles to said shaft, movement of the frame on the rock-shaft operating to carry said 15 stop member into and out of engagement with said stop cam, said stop cam having means associated therewith to prevent the frame from turning on the rock shaft into a position to carry the stop member into op-

erative engagement with the stop cam for a 20 time interval after the belt has been shifted by the belt shifter.

6. In a stop motion, the combination with a driving shaft, of a fast and a loose pulley thereon, a rock shaft, a belt shifter rigid 25 therewith for transferring the belt from one pulley to the other, a frame 25 mounted on the rock shaft for turning movement relative thereto, a stop dog 21 having a stem 30 slidably mounted in said frame, and a spring acting on said stem, said stop cam having provision for preventing the stop member from engaging the periphery thereof for a predetermined time interval after the belt has been shifted onto the loose pulley. 35

In testimony whereof, I have signed my name to this specification.

ELMER C. BASSETT.
